SYNCHRONIZED MICROWAVE GENERATOR

Aly Hassen Abdel Dayem, Alexandria, Egypt, assignor to "Patelhold" Patentverwertungs- & Electro-Holding A.-G., Glarus, Switzerland, a joint-stock company

Application January 4, 1954, Serial No. 402,082

11 Claims. (Cl. 250—36)

The present invention relates to a synchronized microwave generator which is particularly suitable for amplification of frequency modulated microwave signals, but which may also be used as transmitter for amplitude modulated or pulse modulated signals with great carrier frequency stability.

The microwave generator in accordance with the present invention is characterized in that it contains two microwave oscillators which are connected by means of a directional coupler with the synchronizing signal source on the one hand, and with the output circuit of the generator, on the other. In connection therewith the directional coupler prevents a coupling between the synchronizing signal source and the output circuit. The oscillators may be of any suitable construction. It is only necessary that the oscillations which are produced there be may be synchronized by means of a synchronizing signal connected to the output thereof.

An object of the invention is to provide a network for coupling a plurality of microwave oscillators to a common synchronizing source and to a common output circuit in such manner that there can be no transfer of energy between the several oscillators or between the synchronizing source and the output circuit. A further object is to provide a network of the type stated in which the waves produced by the several oscillators neutralize each other at the point where the synchronizing signal is injected into the network, and thus have no back effect upon the synchronizing source. A further object is to provide a network of the type stated in which variations in the impedance of the output circuit can have no disturbing effect upon the several oscillators.

Further objects and advantages in accordance with the present invention will become more obvious from the following description when taken in connection with the accompanying drawing wherein—

Fig. 1 shows schematically one embodiment of the present invention;

Fig. 2 shows a directional coupler which may be used in connection with the present invention; and

Fig. 3 shows a further modified embodiment in accordance with the present invention.

Referring now more particularly to Fig. 1 of the drawing reference numerals O_1 and O_2 designate two microwave oscillators, which are preferably constructed identically. The oscillators O_1 and O_2 are connected by lines L_1 and L_2 with points 1 and 2 lying on a directional coupler of the so-called "hybrid-ring" type. Depending on the particular structure of the generator, this ring may be formed as a closed concentric line or as a closed symmetric line. The coupling points 1 and 2 lie a distance of a half wavelength apart from each other, as measured along the circumference of the ring and the output circuit of the generators is connected at point 3 of the ring which is spaced a distance of a quarter wavelength from point 1 and three-quarters of a wavelength from point 2. The synchronizing signal is injected into the arrangement at point 4, which is in the center be-

2

tween points 1 and 2, so that points 1 and 2 are each spaced a quarter wavelength from such point 4.

In order to facilitate understanding of the operation, it must be remembered, that transmission of energy between two points of the ring can only take place if such points are spaced apart a quarter wavelength or an odd number of quarter wavelengths from one another. Only when the waves which depart from the first point arrive in phase at the second point 2 will there be an energy transfer. A transmission of energy can never take place between two points which are spaced apart a half wavelength or a multiple of a half wavelength because the waves which emanate from the first point arrive in out of phase relationship at the second point.

Referring now to the particular embodiment of the present invention, it becomes obvious that in the arrangement of Fig. 1, a transmission of energy is possible from the two oscillators to the output circuit as well as between the synchronizing signal source and each of the oscillators. However, it is not possible to transfer energy between the synchronizing signal source and the output circuit, and it is also impossible to have any transfer between the oscillators themselves.

In order for the energy at the output circuit to be the sum of the two oscillators O_1 and O_2 , it is necessary that the waves at points 1 and 2 be of opposite phase, as point 2 is a half wavelength nearer the output circuit than point 1. On the other hand, the waves produced by the synchronizing signal source are in phase at points 1 and 2. By making the length l' of line L_2 a quarter wavelength or an odd number n of quarter wavelengths longer than the length l of line L_1 , the waves of oscillator O_2 lag the waves produced by oscillator O_1 by a quarter wavelength or by an odd number of quarter wavelengths. The waves travel through the longer line L_2 in which they are subjected to an additional phase displacement, so that at point 2 the necessary phase difference of 180° with respect to the oscillations at point 1 is obtained. The waves produced by the two oscillators thus are additive at point 3 of the ring which is connected with the output circuit of the generator. On the other hand, the waves produced by the two oscillators O_1 and O_2 arrive at point 4, i. e. the point at which the synchronizing signal is injected, in opposite phase. Under the assumption that the frequencies and the amplitudes of the produced oscillations are equal, there is no back effect of the oscillator waves on the synchronizing signal source. This is a second advantage in accordance with the present invention. The frequencies of the produced oscillations are by force of the synchronization identical. The amplitudes of the two oscillations are not greatly different from each other since they are produced by oscillators of the same construction; it is furthermore possible by any well known device 5, which may permit adjustment of the amplitude of at least one of the oscillators, for example oscillator O_2 , to assimilate the amplitudes of the two oscillators.

If the microwave generator is built as a high frequency waveguide oscillator, then instead of the hybrid-ring, a hollow-tube directional coupler comprising adjacent parallel tubes with an apertured wall in common type may be used, as shown in Fig. 2. In a directional coupler of this type, it is known that no energy is transmitted along the paths indicated by the dotted arrows, while transfer of energy is possible in all other directions. If now the oscillators, the output circuit and the signal source are connected to corresponding points 1 to 4, which correspond to the same points in Fig. 1, then the hollow-tube directional coupler operates functionally analogous to the hybrid-ring. A further description of the operational effect of such arrangement is therefore

not believed necessary and is accordingly dispensed with.

In connection with the use of the arrangement of the present invention as an amplifier for frequency modulated waves, the signal which is to be amplified is injected as a synchronizing signal at point 4 of the arrangement. The frequencies of the waves produced by the oscillators O_1 and O_2 follow that of the synchronizing signal, and the amplified signal will appear at the output 3 of the arrangement, which, for example, may be connected to a transmitter antenna or a further amplifier stage. Changes in the loading of the amplifier, such as are caused, for example, by changes in the antenna impedance within the used frequency range, have no effect on the amplification derived from oscillators O_1 and O_2 . This is a third advantage in accordance with the present invention. As the reflected load variation which is caused by mis-matching the impedances is applied equally to the two oscillators, the mis-match and its influence on the operation of the oscillators is reduced.

For use of the arrangement in accordance with the present invention as a transmitter for amplitude modulated or impulse modulated signals, the waves produced by the two oscillators are simultaneously modulated in amplitude or in the rhythm of the pulses. A wave of the carrier frequency is used as a synchronizing signal. Consequently, this frequency is kept substantially constant even with high degrees of modulation. In connection therewith it should be mentioned that the use of the so-called locked transmitters for purposes of stabilizing the carrier frequency of an amplitude modulated microwave oscillator is known. However such known arrangements do not produce the particular advantages, which are offered by the present invention.

A further possible use of the so far described invention, as shown in Fig. 3, resides in forming each oscillator of two part oscillators.

The reference numeral R_0 identifies the directional coupler which forms the basis of the arrangement already described above. The two oscillators O_1 and O_2 are connected thereto by lines L_1 and L_2 the respective lengths l, l' of which differ by an odd number n of quarter wavelengths. Both oscillators are constructed identically, so that it is only necessary to describe one of the oscillators in detail, namely oscillator O_1 . It consists of two preferably identically constructed part oscillators O_1' and O_1'' which are connected with points a and b of the directional coupler R_1 by lines A and B which are of equal length l_2 . The outlet point c of the directional coupler lies a quarter wavelength from points a and b , as measured along the ring of the directional coupler. If the two part oscillators operate in phase or cophasially, then the sum of the waves produced by the two part oscillators appears at outlet point c . This sum of the waves is then transmitted via line L_1 to the directional coupler R_0 of the microwave generator. On the other hand, a part of the synchronizing signal is conducted to the oscillator O_1 over the same line, this signal being derived from the synchronizing signal source connected to point 4 of the directional coupler R_0 . The directional coupler R_1 distributes this signal cophasially to the two part oscillators O_1' and O_1'' so that the same, as assumed above, actually operate cophasially.

The symmetry in the manner of operation of the two part oscillators is enhanced if a reflectionless matched impedance W is connected to the fourth point of the directional coupler R_1 , i. e. to the point d . The provision of this impedance offers the further advantage that with stoppage of one of the part oscillators a definite load impedance is provided for the other part oscillator.

The adjustment and monitoring of the microwave generator may be done in a particularly advantageous manner by providing a meter M for measuring the high frequency energy in the impedance W since the value thereof reaches a minimum with proper operation of the system.

It is further possible to provide a further sub-division in such manner that each part oscillator O_1' and O_1'' is formed of a plurality of oscillators. As the foregoing considerations and descriptions are equally applicable to such case, a further detailed description is not necessary.

If the microwave generator is constructed as a wave-guide-type, then the directional coupler is used in place of the hybrid rings, as has been indicated already above. The directional coupler permits the operation of the microwave generators over a considerably larger frequency band than is possible with ring type directional couplers. However, the band width of the latter is sufficient for all practically used modulating types with a given carrier frequency.

I claim:

1. A synchronizing microwave generator comprising two substantially identical microwave oscillators having substantially the same operating frequencies, a synchronizing signal source, a common output circuit for said oscillators, and directional coupler means for coupling said oscillators individually with said source and jointly with said output circuit.

2. Microwave generator according to claim 1 wherein the transmission lines connecting said oscillators with said directional coupler differ by an odd number of quarter wavelengths.

3. Microwave generator according to claim 1 wherein said directional coupler is a hybrid ring.

4. Microwave generator according to claim 1 wherein said directional coupler comprises adjacent parallel tubes having a common apertured wall.

5. Microwave generator according to claim 1 further comprising means for varying the amplitude of at least one of said oscillators to assimilate the amplitudes of said oscillators.

6. A synchronizing microwave generator comprising two microwave generators each of which includes two microwave oscillators, a directional coupler for each generator, each of said directional couplers having an outlet point therein, transmission lines connecting the microwave oscillators of each generator to the directional coupler thereof at points spaced from the outlet point thereof by an odd number of quarter wavelengths, an output circuit, a synchronizing signal source, a main directional coupler having said output circuit and said synchronizing signal source connected thereto at points spaced apart by a half wavelength, transmission lines which differ in length by an odd number of quarter wavelengths connecting the output points of the directional couplers of said generators to points on said main directional coupler spaced a quarter wavelength from the points of connection of both said synchronizing signal source and said output circuit.

7. Microwave generator according to claim 6 wherein said directional couplers are formed as hybrid rings.

8. Microwave generator according to claim 6 wherein said directional couplers are formed as wave guide couplers.

9. Microwave generator according to claim 6 wherein each oscillator consists of a plurality of oscillators.

10. Microwave generator according to claim 6 wherein a matched impedance is connected to each directional coupler of said generators.

11. Microwave generator according to claim 10, in combination with means for measuring the energy in said impedance.
